United States Patent Office

Des. 178,165
Patented June 26, 1956

178,165

TABLE ORNAMENT

Adelaide S. West, Chicago, Ill.

Application June 27, 1955, Serial No. 36,713

Term of patent 14 years

(Cl. D58—11)

Fig. 1

Fig. 2

I claim:

The ornamental design for a table ornament, substantially as shown.
